US00D490406S

(12) **United States Design Patent** (10) Patent No.: **US D490,406 S**
He et al. (45) Date of Patent: **** May 25, 2004**

(54) **KEYPAD FOR A HANDSET**

(75) Inventors: **Jiang Yuan He**, Shenzhen (CN);
Xiaozhou Wang, Shenzhen (CN);
Chia-Hua Chen, Tu-chen (TW)

(73) Assignee: **Hon Hai Precision Ind. Co., Ltd.**,
Taipei Hsien (TW)

(**) Term: **14 Years**

(21) Appl. No.: **29/173,348**

(22) Filed: **Dec. 27, 2002**

(51) LOC (7) Cl. **14-03**

(52) U.S. Cl. **D14/247**
